UNITED STATES PATENT OFFICE.

CHARLES W. DAKE, OF CHICAGO, ILLINOIS, ASSIGNOR OF ONE-HALF TO CYRUS W. RICE, OF GRAND RAPIDS, MICHIGAN.

PANELED STRUCTURE.

1,371,667.

Specification of Letters Patent.

Patented Mar. 15, 1921.

Application filed March 1, 1920. Serial No. 362,409.

To all whom it may concern:

Be it known that I, CHARLES W. DAKE, a citizen of the United States, residing at Chicago, in the county of Cook and State of Illinois, have invented new and useful Improvements in Paneled Structures, of which the following is a specification.

The present invention relates to paneled structures; and its general object is to provide an improved structure of that character; a more particular object is to provide such a structure comprising a peripheral member having a recess extending from its inner surface, and a panel having a peripheral transversely-extending portion inserted into said recess and securely held therein by a retaining member; a further more particular object is to provide such a structure comprising a peripheral member having a recess extending from its inner surface provided with a transverse extension, and a panel having a peripheral transversely-extending portion inserted into and securely held in said recess and its said extension; a further more particular object is to provide such a structure having a peripheral member as above described, and a pair of panel members disposed side by side and provided with such transverse extensions inserted into and securely held in the recess; a further particular object is to provide a structure comprising a peripheral member of conjoined parts each having a recess extending from its inner surface, and a panel having a transversely-extending portion inserted into and securely held in said recess; a further more particular object is to provide means for preventing the expansion and contraction of the panel from exercising undue stresses on the peripheral member; a further object is to provide such a structure very effectively held together and braced against diagonal and other stresses.

These and any other objects hereinafter appearing are attained by, and the invention finds preferable embodiment in, the structure or structures hereinafter particularly described and illustrated by the accompanying drawings, in which:

50 Figure 1 is a front view of a paneled structure embodying my invention;

Fig. 2 is a sectional view (enlarged) of a portion thereof taken on a plane corresponding to line 2—2 of Fig. 1;

55 Fig. 3 is a like view, but showing a modi-

fied construction in which the peripheral member's panel-holding recess has a transverse extension, and the panel has no cross-sectionally deflected portion;

Fig. 4 is a like view, but showing another modified construction in which a pair of panel members are disposed side by side;

Fig. 5 is a sectional view of the upper portion of a panel member taken on a plane corresponding to line 5—5 of Fig. 1;

Fig. 6 is a view of a corner portion of said panel member, looking toward its concave side; and

Fig. 7 is a view in perspective of a portion of a retaining member which secures the panel member in the peripheral member's recess.

In the embodiments of the invention chosen for illustration by the accompanying drawings and for detailed description in the body of this specification, the panel structure comprises a peripheral member A and a metallic panel member B, B¹, or a pair of panel members B². The peripheral member A and each of its conjoined parts (the stiles G and rails H) has a recess A¹ extending from its inner surface A². The panel member has a peripheral flange or transversely-extending portion B³ adapted to be inserted into the recess A¹. In the forms particularly shown in Figs. 3 and 4, the recess A¹ is provided with a transverse extension A³. In all the forms shown the panel is securely held in the recess A¹ by a suitable retaining member, in form a strip C, inserted into and secured in the recess to closely engage a side thereof and a side of the panel. In the form shown in Fig. 3, the transversely-extending portion B³ of the panel is inserted into and securely held in the transverse extension A³ of the recess A¹, while in the form shown in Fig. 4, such portion B³ of one of the panels is thus inserted into and held in such extension A³; but in the form shown in Fig. 2, the panel is securely held in the recess A¹ by the retaining member C whose inner edge abuts against the adjacent side of the panel's transversely extending portion B³. In Fig. 4 the pair of panels B², disposed side by side, have in their middle portion an intervening member E.

Means are shown in Figs. 1 and 2 for preventing the expansion and contraction of the panel from exercising undue stresses on the peripheral member, such means being the

forming of the panel with a cross-sectionally deflected portion adjacent its periphery, such portion being preferably thus deflected inwardly at B^4 and then outwardly at B^5 , as particularly shown in Fig. 2.

In assembling the structure, the parts (as the stiles G and rails H) are formed with their recesses A^1 ; these parts are joined together in any suitable or well-known manner, with the peripheral transversely-extending portions B^3 of the panel in the recesses: the retaining members C are now driven into the recesses and securely held therein in any well-known manner, as by gluing or tacking.

It will be seen that the completed structure is very effectively braced against diagonal and other stresses and its parts held together by the engagement of the panel's transversely-extending peripheral portions with the transverse extensions of the recesses (as in Figs. 3 and 4), or with the securely held retaining member (as in Fig. 2). The metallic panel may be readily formed by bending the edges D of a metallic sheet to form the panel's peripheral transversely-extending portions B^3 as indicated in Fig. 6.

The invention being intended to be pointed out in the claims, is not to be limited to or by details of construction of the particular embodiment thereof shown by the drawings or hereinbefore described.

I claim:

1. In a structure of the character described; a peripheral member having a recess extending from its inner surface parallelly with the panel hereinafter mentioned; a panel having adjacent its periphery a transversely-extending portion, which portion is inserted into said recess; a retaining member secured in the recess and closely engaging a side thereof and a side of the panel inserted thereinto and engaging said transversely-extending portion of the panel.

2. In a structure of the character described; a peripheral member having a recess extending from its inner surface parallelly with the panel hereinafter mentioned and provided with a transverse extension; a panel having adjacent its periphery a transversely-extending portion, which portion is inserted into said recess and into its said extension; a retaining member secured in the recess and closely engaging a side of the main portion thereof and a side of the panel.

3. In a structure of the character described; a peripheral member having a recess extending from its inner surface parallelly with the panel hereinafter mentioned and provided with a transverse extension; a pair of separable panels disposed side by side and having respectively oppositely disposed transversely-extending portions adjacent their peripheries, which portions are inserted into said recess one said portion be-

ing inserted into said extension; a retaining member secured in the recess and closely engaging a side thereof and a side of one panel and the transversely-extending portion thereof.

4. In a structure of the character described; a peripheral member comprising conjoined parts interrelatively inclined, each having a recess extending from its inner surface parallelly with the panel hereinafter mentioned; a panel having adjacent its periphery transversely-extending portions which portions are inserted into said recesses respectively retaining members secured in the respective recesses and closely engaging a side thereof and a side of the panel.

5. In a structure of the character described; a peripheral member having a recess extending from its inner surface parallelly with the panel hereinafter mentioned; a panel having adjacent its periphery a cross-sectionally deflected portion and having nearer its periphery a transversely-extending portion which is inserted into said recess; a retaining member secured in the recess and closely engaging a side thereof and a side of the panel.

6. In a structure of the character described; a panel having adjacent its periphery a transversely-extending portion; a peripheral member having a recess extending from its inner surface parallelly with said panel, into which recess the panel's transversely extending portion is inserted; means for securely holding the panel's said portion in said recess.

7. In a structure of the character described; a peripheral member having a recess extending from its inner surface parallelly with the panel hereinafter mentioned; a pair of separable panels disposed side by side and having recesses in the middle portions of their adjacent sides, and peripheral portions inserted into said recess; a panel member retained in the panels' recesses; a panel-retaining member secured in the peripheral member's recess.

8. In a structure comprising a peripheral member composed of interrelatively inclined parts each having a recess extending from its inner surface parallelly with the panel hereinafter mentioned; the method of forming a panel to be inserted into said recesses which method consists in cutting off the corners of a metal sheet on lines inclined to the sheet's adjoining edges respectively and bending portions of the sheet on lines substantially parallel with said edges respectively, to form peripheral transversely-extending portions of the panel adapted to be inserted into said recesses respectively.

In testimony whereof I have hereunto set my hand at Grand Rapids, Michigan, this 21st day of February, 1920.

CHARLES W. DAKE.
